(57) **CLAIM**

The ornamental design for a trim for air intake, as shown and described.

DESCRIPTION

FIG. 1 is a front, left perspective view of a trim for air intake showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

A second embodiment of the claimed design for the trim for air intake is a mirror image of the trim for air intake as shown in FIGS. 1 to 7.

1 Claim, 4 Drawing Sheets
